UNITED STATES PATENT OFFICE

2,161,543

METAL DRUM

Erwin Wandrey, Chicago, Ill., assignor to R. B. Hayward Company, Chicago, Ill., a corporation of Illinois

Application September 23, 1938, Serial No. 231,437

1. Claim. (Cl. 242—77)

My invention relates generally to metal drums, but more particularly, though not exclusively, to drums forming parts of reels provided, as for example, for the winding thereon of electric cable, or the like, and more especially reels formed of spaced apart heads between which the drum portion is interposed and secured, as for example by tie rods extending from head to head through inwardly extending portions at the ends of the drum.

One of my objects is to improve upon the constructions of metal drums especially of the character above referred to as hitherto provided, to the end of producing a construction which will afford better service and be more economical of manufacture and of lighter weight than constructions as hitherto provided.

Another object is to provide a drum structure fabricated of a metal shell and reinforcing, stiffening, annular members welded in position in the ends of the shell and which will not be subject to objectionable deformation in the subjection of the structure to heat in the galvanizing thereof.

Another object is to provide a construction of drum of the character stated, with its shell portion constructed of high carbon steel of relatively light gage, such as for example No. 16 gage, presenting great resistance to denting in use and which will not be subject to objectionable deformation in the subjection of the shell, with the reinforcing annular members welded thereto, to galvanizing heat.

Another object is to provide a construction of drum presenting the desired strength and which when secured in interposed position between the heads of a reel will present in conjunction with the inner faces of the heads annular right angled corners the provision of which insures the proper positioning of the cable, or the like, even when of small diameter, about the circumference of the shell; and other objects as will be manifest from the following description.

Referring to the accompanying drawing:

Figure 1 is a view in front elevation of a reel of the general character above referred to comprising, as an element thereof, a drum constructed in accordance with my invention, portions of the shell of the drum being broken away to disclose interior details.

Figure 2 is a section taken at the line 2 on Fig. 1 and viewed in the direction of the arrow.

Figure 3 is an enlarged fragmentary sectional view taken at the line 3 on Fig. 2 and viewed in the direction of the arrow; and

Figure 4, an enlarged fragmentary sectional

view taken at the line 4 on Fig. 2 and viewed in the direction of the arrow.

Referring to the illustrated construction, it comprises a pair of circular heads 5 and 6, and an interposed drum 7 embodying my invention, the heads and drum being secured together as hereinafter described.

The drum 7 which is made of metal comprises a cylindrical shell 8 which may be formed in any suitable way from sheet metal such as for example sheet steel and more particularly high carbon sheet steel as such kind of steel is much less susceptible to denting than the low carbon steels.

The drum 7 also comprises metal bands 9 located in the ends of the shell 8 and shown set back a slight distance from the adjacent ends of the shell to receive the rings hereinafter referred to.

Each band 9, by way of example may be formed of a single length of suitable metal bent into substantially circular form and, in the springing thereof into place in the ends of the shell 8, snugly fitting the inner periphery of the shell. The bands 9 at intervals spaced apart about the circumferences thereof are welded to the shell. Preferably, and as shown, the welding of these bands to the shell is effected by forming openings 10 at intervals in each band, these openings preferably being somewhat elongated in the direction of the circumference of the band, and welding the bands to the shell through the openings 10, the metal of the welds being represented at 11. While the welding through openings in the bands is preferred as stated, the welding of the bands at spaced apart points about their circumferences may be effected in other ways as for example by spot welding the bands to the shell or welding them thereto at the junctures of the inner edges of the bands with the inner periphery of the shell.

The drum also comprises rings 12 located in the ends of the drum, these rings, which extend transversely of the drum as shown, extending at their outer margins into the interior annular angles formed at the junctures between the outer edges of the bands 9 and the portions of the shell 8 projecting beyond these bands, the ends of the shell being substantially flush with the outer faces of the rings 12.

The rings 12 are secured to the bands 9 by welding these parts together, there being no direct connection between the rings 12 and the shell 8.

The rings 12 are preferably welded to the adjacent bands 9 at spaced apart points along the

interior annular angles formed by the inner faces of the rings 12 and the inner peripheries of the bands 9, as represented at 13, this welding being effected at spaced apart points about the bands, as represented, the welds 13 preferably alternating with the welds 11 with each weld 13 equidistantly spaced from the adjacent welds 11 as clearly illustrated in Fig. 2.

The bands 9 and the rings 12 which form 10 stiffening and reinforcing means for the shell, and may, by way of example, be made of low carbon steel, are of a thickness relatively great compared to the thickness of the sheet metal of the shell 8 which latter may be as thin as $\frac{1}{16}$ inch.

15 The bands 9 may be about $\frac{1}{8}$ inch thick and from $\frac{1}{2}$ to $\frac{5}{8}$ inch wide and the rings 12 about $\frac{1}{16}$ inch thick and from $1\frac{1}{2}$ to 3 inches deep. It will be understood, however, that the dimensions above given are only by way of example and that 20 no limitation of the invention thereby is intended.

25 The heads 5 and 6 and drum 7 are shown as secured together by tie bolts 14 which extend continuously through openings in the heads 5 and 6 and through openings 15 in the rings 12.

30 As will be understood, the desired thickness of metal at the ends of the drum to resist shear at the bolts 14 may be provided, without regard to the gage or kind of metal of which the shell 8 is formed, by reason of the provision of the annular members in the ends of the shell. Thus I am enabled to avail myself, in a highly practical construction, of the advantage of using high carbon steel for the shell 8 to prevent denting, while providing the necessary thickness of metal at the 35 bolt holes in the drum to present the desired resistance to shear; a condition not possible of attainment where the bolt engaging flanges of the drum are formed by turning inwardly the ends of the metal sheet of which the shell of the 40 drum is formed, except by forming the shell of such thickness as to render the reel expensive to manufacture and of objectionable weight.

45 As will be noted, the interior annular angles between the inner faces of the heads 5 and 6 and the shell 8 are of right angled form as distinguished from a construction in which the ends of the shell are rounded over inwardly toward the center of the shell, and thus a cable, or the like, even when of small diameter, wound upon the

drum, occupies the desired position about the shell.

5 Drum structures for reels are commonly galvanized before assembly with the heads, by immersing them in a galvanizing bath of suitable molten metal the heat of which causes stresses existing in the fabricated structure as a result of welding the parts together, to become relieved. Provision for preventing such relief of the stresses from producing objectionable deformation of the 10 drum are necessary. This is accomplished by my built-up drum, the welding of the rings 12 to the bands 9 at spaced apart intervals at 13, staggered with relation to the welds 11, being preferred as thereby the cost of manufacture and deformation 15 resulting from the heat of galvanization are minimized.

In accordance with the particular construction shown the rings 12 need not accurately fit the ends of the shell and thus do not require to be 20 machined which is a great factor in minimizing the cost of construction.

25 While I have illustrated and described a particular construction embodying my invention and suggested certain modifications thereof I do not 25 wish to be understood as intending to limit it thereto as the structure shown may be modified and altered in other ways, and the invention embodied in other forms without departing from the spirit of the invention.

30 What I claim as new and desire to secure by Letters Patent, is:

35 A metal drum comprising a drum-wall-forming shell, bands in the ends of said shell and set back from the terminal edges thereof, said bands having openings therethrough, weld means in said openings securing said bands to said shell at spaced apart intervals around the bands, rings located in the ends of said shell outwardly beyond 40 said bands, the outer faces of said rings being substantially flush with the terminal edges of said shell, weld means securing adjacent ones of said bands and rings together at spaced apart intervals around the rings and disposed in staggered 45 relation to said first-named welds and substantially equidistantly spaced from adjacent ones of said first-named welds, said rings being free of connection with said shell.

ERWIN WANDREY.
